Inventor:

John F. Mossberg,
By his Attorneys.

Williamson & Merchant

UNITED STATES PATENT OFFICE.

JOHN F. MOSSBERG, OF MINNEAPOLIS, MINNESOTA.

CATAPHORIC PAD.

SPECIFICATION forming part of Letters Patent No. 679,239, dated July 23, 1901.

Application filed December 10, 1900. Serial No. 39,303. (No model.)

To all whom it may concern:

Be it known that I, JOHN F. MOSSBERG, a citizen of the United States, residing at Minneapolis, in the county of Hennepin and State 5 of Minnesota, have invented certain new and useful Improvements in Cataphoric Pads; and I do hereby declare the following to be a full, clear, and exact description of the invention, such as will enable others skilled in 10 the art to which it appertains to make and use the same.

My invention has for its object to provide a device in the nature of a cataphoric pad or body-gear adapted to be worn on a person 15 for the continuous application of electric osmose.

To the above end the invention consists of the novel devices and combinations of devices hereinafter described, and defined in 20 the claims.

The device which I style a "cataphoric pad" involves a pair of electrodes with absorbent pads or faces, an electric circuit including a battery, and a suitable body-gear for supporting the parts in proper position upon the body. This gear may take various forms, 25 but for ordinary use is constructed substantially as shown in the drawings.

In the illustration of the invention given 30 in the drawings like characters indicate like parts throughout the several views.

Figure 1 is a perspective view of the complete device, some parts being broken away. Fig. 2 is a plan view of one of the electrodes 35 and its absorbent pad or facing. Fig. 3 is a section on the line $x^3 x^3$ of Fig. 2. Fig. 4 is a plan view of a portion of the battery, some parts being broken away; and Fig. 5 is a view looking at the edge of the section of the battery shown in Fig. 4.

The numeral 1 indicates a suitable belt which is formed with a longitudinally-extended pocket 2, in which the battery 3 is placed. This battery 3 is of ordinary or any 45 suitable construction, being, as shown, made up of outer link-sections 3^a , of brass, inner link-sections 3^b , of zinc, acidulated packings 3^c , and connecting-links 3^d . The belt 1 is shown as made adjustable by buckle 1^a .

The electrodes 4 and 5 are of any suitable plate or flexible metal cut to the proper form. As shown, these electrodes are afforded by

thin perforate metal plates; but it will be understood that a wire-gauze will be serviceable for the same purpose. The electrodes 4 and 5 are embedded between absorbent pads or facings 6 and leather or other suitable covers or backs 7, which parts 6 and 7 are suitably secured together at their margins. A pair of shoulder-straps 8, adjustable by means of 55 buckles 8^a , connect the backs 7 of the two electrodes 4 and 5. A pair of back straps 9 connect the backs 7 of the electrode 4 with the belt 1.

The electrode 5 has a flanged projection 10, 65 to which a metallic clamp, made up of pivotally-connected jaws 11 12, is detachably secured. The jaw 12 is the movable member and, as shown, is subject to a spring 13. The upper end of a strap 14 is secured to the 70 lower end of the jaw or member 11, and the lower end of this strap 14 is formed with a loop 15, which embraces the belt 1 and is adapted to slide thereon.

The battery 3 is connected at one end to 75 the electrode 4 by an insulated wire 16, which is run up through one of the straps 9. The other end of said battery 3 is connected with the clamped jaw 11 and by it with the electrode 5 by means of an insulated wire 17, 80 which, as shown, runs for some distance within the body of the belt 1, is given a loose loop 18 after it leaves the belt, and is then run upward through the strap 14. The lower end of the strap 14 is adapted to be slid upon the 85 belt 1, so that it may always be kept diametrically opposite to a vertical line drawn through the center of an electrode 4, regardless of the adjustment of the belt 1. This permits the pad of the electrode 4 always to 90 be located centrally on the wearer's back and the pad of the electrode 5 to be located centrally on the wearer's breast regardless of the required adjustment in fitting the device to the person.

It has already been indicated and will be here more positively stated that the salient object of this invention is to provide a device which may be constantly worn and which will afford means for the continuous application 95 of electric osmose for therapeutic purposes in contradistinction to the ordinary devices in which the simple application of the electric current is provided for.

It is of course a well-known fact that a continuous electric current has the property of carrying with it a medicament or fluid which lies in its path. Thus it is that in accordance with my invention the electrodes are themselves held out of contact with the body of the person and are provided with the absorbent pads or facings. These absorbent pads or facings (indicated in the drawings by the numeral 6) are when the device is to be used saturated with the medicament, which is applied in liquid form. The gear is properly adjusted upon the body of the wearer, so that the part to be treated will lie in the direct path between the two electrodes, and the said saturated pads are thus applied next to the skin. This being done, the cataphoric action of the continuous current from the battery will by a slow but continuous process drive or carry the medicament through the skin into the body.

I believe I am the first to provide a device of the above character which is capable of continuous wear.

What I claim, and desire to secure by Letters Patent of the United States, is as follows:

1. The combination with the belt 1 having the pocket 2, of the battery within said pocket, the electrodes 4 and 5 having the absorbent pads or facings 6 and backs 7, the shoulder-straps connecting said backs 7, the straps 9 connecting said belt with one of said backs 7, the strap 14 connecting the said belt with the other electrode, and circuit connections between said battery and said electrode, substantially as described.

2. The combination with the belt 1 having the pocket 2, of the battery within said pocket 2, the electrodes 4 and 5 having the absorbent pads or facings 6 and backs 7, the shoulder-straps connecting said backs 7, the straps 9 connecting said belt with one of said backs 7, the strap 14 and clamp 11, 12, connecting the belt with the other electrode, and circuit connections between said battery and said electrodes, substantially as described.

In testimony whereof I affix my signature in presence of two witnesses.

JOHN F. MOSSBERG.
